UNITED STATES PATENT OFFICE.

THOMAS J. RICHARDS, OF YOUNGSTOWN, OHIO.

AUTOMATIC ELECTRICAL HEAT-TREATING DEVICE.

1,385,473.

Specification of Letters Patent. Patented July 26, 1921.

Application filed August 25, 1919. Serial No. 319,571.

To all whom it may concern:

Be it known that I, THOMAS J. RICHARDS, a citizen of the United States of America, residing at Youngstown, in the county of Mahoning and State of Ohio, have invented certain new and useful Improvements in Automatic Electrical Heat-Treating Devices, of which the following is a specification.

This invention relates to automatic electrical heat treating devices and has for its principal object to measure temperature by direct expansion of the matter being heated electrically or otherwise.

Another object of my invention is to so arrange the device that the matter to be treated and measured will feed by gravity into the device, which has a quenching bath below the device into which the matter will travel by gravity when released.

With these and other objects in view the invention consists in the novel details of construction and combination of parts more fully hereinafter disclosed and particularly pointed out in the claim.

25 In the accompanying drawings:—

Figure 1 is a top view of the device.

Fig. 2 is a front elevation of the device.

Fig. 3 is a detail view showing diaphragm and connecting parts in a vertical position.

30 Fig. 4 is a detail sectional view.

Referring more particularly to the drawings, wherein one embodiment of my invention is illustrated: 1 designates any suitable base upon which the device rests. The electrodes 2 are cored for water circulation, held in position by supporting members 3. (See Fig. 1.) By referring to Fig. 1 it will be seen that I have provided an intake water tube 4 and an outlet water tube 5 which 40 empties into an escape pipe 6.

In operating this device, the article to be heated to some desired temperature is fed into the opening between the electrodes 2 by means of a master controller 7.

45 The master controller 7 pulls down the arm 8 by means of a solenoid 9, thereby turning the screw 10 so as to firmly grip the matter to be heated between the electrodes 2.

This pressure exerted on the lever 11 50 causes the fluid in the diaphragm 14 to rise in the tube 15. The master controller then opens the valve 18 by means of a solenoid 17, which is timed for the operation. The fluid in the tube then flows back into a reservoir 19 until the fluid reaches a common 55 level. The valve 18 is now automatically

closed, thereby setting the device at zero. By the term "zero" is meant the fixed fluid level secured by opening of the valve 18.

The master controller 7 then turns on the electric current into the electrodes 2, thereby causing the matter between the same to become heated.

By referring to Fig. 1, it will be seen that I have provided a lever 11 hinged at point 12, having on the side thereof a dog 13, which is held against the electrode 2, which is opposite the electrode 2, which is in contact with the screw 10.

The heat produced in the matter between the electrodes 2 causes the matter held between them to expand, which forces the lever 11 so that the end of the same comes in contact with a diaphragm 14. This diaphragm is filled with a fluid, preferably mercury. The outward pressure of the lever 11 causes the diaphragm 14 to shorten, thereby forcing the mercury into the tube 15.

When the mercury reaches a predetermined point it comes in contact with a rod 20 projecting down into the upper end of the tube 15. This rod 20 can be adjusted by means of a thumb screw 21. When the mercury reaches this point 20, the circuit to the electrodes 2 is opened and a circuit contact is made, whereby the master controller 7 acts on the solenoid 24, thereby releasing the matter between the electrodes 2, and the matter travels by gravity into a quenching tank of any suitable construction.

In order to determine and control the current entering the electrodes 2 a rheostat 22 is located in the circuit carrying the current to the electrodes 2.

By referring to Fig. 1, it will be seen that I have provided a coil spring 23 which holds the dog 13 against the electrode 2.

In treating a number of similar articles, the same operation is automatically repeated, thereby securing an equal temperature of like articles before releasing them into the quenching bath.

It will be readily understood that by this process, metals requiring tempering can be made uniform as to the heat subjected to them before being released to the quenching bath.

While I have shown specific detail, I do not wish to be held to the exact construction shown in so far as compelled by the claim.

What I claim is:—

In a device of the class described, the

combination of two support members, two water cooled electrodes positioned diametrically opposite each other and secured within said support members, a screw member having one end registering with one of said electrodes, a threaded opening centrally located in one of said support members, an arm securely fastened to the other end of said screw member, solenoids located under 5 outer ends of said arm and connected to ends of said arm, means for operating said solenoids, a lever pivoted to one of said support members, a dog formed on the side of said lever, said dog located so as to register with outer surface of an electrode, a coil spring 15 positioned at outer end of above mentioned arm, substantially as described for the purpose set forth.

In testimony whereof I affix my signature.

THOMAS J. RICHARDS.
